UNITED STATES PATENT OFFICE

112,513

DESIGN FOR A METAL CAP FOR BOTTLES

Leslie R. N. Carvalho, Toledo, Ohio, assignor to
Owens-Illinois Glass Company, Toledo, Ohio,
a corporation of Ohio

Application October 6, 1938, Serial No. 80,294

Term of patent 14 years

To all whom it may concern:

Be it known that I, Leslie R. N. Carvalho, a citizen of the United States, residing at Toledo, in the county of Lucas and State of Ohio, have invented a new, original, and ornamental Design for a Metal Cap for Bottles, of which the following is a specification, reference being had to the accompanying drawing, forming a part thereof.

In the drawing:

Fig. 1 is a side elevational view of a metal cap for bottles showing my new design.

Fig. 2 is a top plan view thereof.

I claim:

The ornamental design for a metal cap for bottles, substantially as shown.

LESLIE R. N. CARVALHO.
